UNITED STATES PATENT OFFICE.

SALVATORE D. POMPANO, OF EAST HAVEN, CONNECTICUT.

TOOL FOR INSERTING AND EXTRACTING PINS AND WASHERS.

Application filed June 9, 1928. Serial No. 284,031.

The present invention relates to tools of a certain class employed for inserting and extracting washers and pins. The improved tool is particularly useful in such instances 5 where the washers or pins or the like are located in places which are comparatively difficult of access so that an ordinary pair of pliers or similar tool cannot be conveniently operated.

10 The improved tool is designed for several purposes, one purpose being to operate with ordinary straight headless pins and for this purpose two pairs of gripping jaws are provided on the tool so that the proper pair may 15 be selected, one pair of jaws being useful for operation on vertically arranged pins and the other, for horizontally arranged pins. The tool is also provided with jaws or means for holding or gripping washers, particularly the 20 open slotted or horseshoe washers commonly used with motor vehicles. Furthermore, means are provided on the tool for extracting cotter pins. Each device or member of 25 the tool performs its separate function but these members are rendered operative by a common member or members in such a manner that the several devices or members are co-operative in their action. The invention 30 will be more fully described hereinafter with reference to the accompanying drawings, wherein—

Figure 1 is a plan view of the complete tool in one position of operation where the jaws are closed to grip a pin;

35 Figure 2 is a plan view showing the tool with the pin gripping jaws open and the jaw for holding washers in its closed position;

Figure 3 is a plan view of the same tool 40 showing the pin gripping jaws in the closed position and the washer gripping jaw in its full open position;

Figure 4 is a detail view of a piece which carries the two movable jaws of the tool;

45 Figure 5 is a detail view showing the operating plate or member of the tool, and

Figure 6 is a plan view of the body of the tool.

Referring to said drawings, the complete 50 tool consists of the body member 1 which is preferably a drop forging or, if desired, a casting may be employed. The tool is enlarged at one end to provide a head 2 and this head is cut out to form a seat 3 for a washer 55 which is an ordinary open slotted type com-

monly used on motor vehicles. The opposite end of the member 1 is enlarged to provide a head in which a seat is formed for a separate piece 4 carrying the movable jaws 5 and 6 and which piece is arranged to turn on 60 pivot pin 7. The fixed or immovable members of the jaws are formed by integral projections or extensions 8 and 9 on the body member 1. The operative member of the tool consists of a plate 10 which is movable so as 65 to slide on the body member 1. Screws or pins 11 hold the plate 10 in operative relation with the body member 1 and which pins 11 lie within slots 12 which limit the sliding movement of said plate 10.

70 When the sliding plate 10 is in the position shown in Figure 1, the bifurcated ends 13 partly cover the washer which is placed in the jaw or seat 3 and in this same position of the plate, the pin gripping jaws are both closed 75 so that the vertically arranged jaws 5—8 would grip a vertical pin such as α or the horizontally arranged jaws 6—9 would grip the horizontal pin β and to enhance the gripping action of the jaws, each jaw has the 80 groove 14.

85 In the position shown in Figure 1, the jaws are closed and it will be noted that the pin or screw 15 is in an angular position relatively to the pivot 7 and which pin is within the radius slot 16. To effect opening of the jaws, the sliding plate 10 is thrown into the 90 position shown in Figure 2 and to facilitate operation of this plate, the lug 17 is provided thereon. The relative position of the pin 15 with the pivot 7 is such that when the plate is brought to the extreme position, in the direction of the indicating arrow c , the result 95 is that the movable jaws 5—6 will open as shown. In Figure 3, the jaw for holding the washer is completely open so that the washer may be readily inserted therein and when the bifurcated members 3 are pushed over to completely or partly cover the washer, the latter is firmly held in place so that it may 100 be seated where required with facility and furthermore, this gripping action will also serve to hold the washer which is to be removed.

105 The jaws for removing and inserting pins are in pairs, one pair being in alignment with the body of the tool and these jaws are employed for removing horizontal pins. The other jaws lie at right angles to the body and these jaws are employed for removing or in- 110

serting vertical pins. A further device consisting of the spur 18 is carried on the tool and this device is employed for removing cotter pins. One way of operating this device is shown by broken lines in Figure 1 and in this case the hook or spur 18 is engaged in the looped head of the cotter pin 19. The bolt or nut with which the pin is associated provides the rest for the fulcrum of the tool and which fulcrum is the horizontal stationary jaw 9. With this arrangement, the cotter pin is readily engaged by the hook device under a leverage action, the clinched ends of the cotter pin are brought together and pulled through the hole in the end of the bolt, for example.

Various modifications may be made in carrying out the details of the invention hereinbefore described and it is to be understood that any modification coming fairly within the terms of the appended claims shall be covered thereby.

I claim—

1. A device of the class described having a body member, a plate slidably mounted on said body, a pair of jaws at one end of said body substantially in alignment therewith, another pair of jaws extended at substantially right angles to said body, said jaws having stationary and movable members, said movable members of both jaws being carried by one piece pivotally mounted on said body and said plate operating to open and close said movable jaws.

2. A device of the class described having a body member, a plate loosely mounted on said body, a pair of jaws at one end of said body substantially in alignment therewith, another set of jaws extended at substantially right angles to said body, said jaws having stationary and movable members, said movable members of both jaws being carried by one piece pivotally mounted on said body, said plate moving to open and close said movable jaws and means for operating and for limiting the movement of said plate.

3. A tool of the class described comprising a body, gripping jaws at one end of said body adapted for holding pins, a gripping jaw at the opposite end of said body adapted to receive and hold washers and a common oper-

ating means for all of said jaws comprising a plate slidably mounted on said body.

4. A tool of the class described comprising a body, a set of gripping jaws at one end of said body, said jaws having movable and fixed members, a sliding plate for opening and closing said jaws and an extracting hook extending from said body operative with one of said fixed members as a fulcrum therefor.

5. A tool of the class described comprising a body, two pairs of gripping jaws located at one end of the body at right angles to each other, a pivoted member carrying the movable jaws of both pairs of gripping jaws, the immovable jaws forming integral parts of said body, a gripping or holding jaw at the opposite end of said body member and a common operating plate for all of said gripping or holding jaws.

6. A tool of the class described comprising a body, two pairs of gripping jaws located at one end of the body at right angles to each other, a pivoted member carrying the movable jaws of both pairs of gripping jaws, the immovable jaws forming integral parts of said body, a gripping or holding jaw at the opposite end of said body member, a common operating plate for all of said gripping or holding jaws slidably mounted on said body and the movement of said plate being guided and limited by pin and slotted connections between said plate and said body.

7. A tool of the class described comprising a body, two pairs of gripping jaws located at one end of the body at right angles to each other, a pivoted piece carrying the movable members for both pairs of gripping jaws, immovable members of said jaws forming integral parts of said body, a gripping or holding jaw at the opposite end of said body member, a common operating plate for all of said gripping or holding jaws slidably mounted on said body and a depending hooked lug operating as an extractor and operating with one of said immovable members as a fulcrum therefor.

Signed at New Haven, county of New Haven, State of Connecticut, this 8th day of June, 1928.

SALVATORE D. POMPANO.
